UNITED STATES PATENT OFFICE.

WILLIAM F. DRAPER, OF HOPEDALE, MASSACHUSETTS.

LOOM-SHUTTLE.

No. 909,377.

Specification of Letters Patent. Patented Jan. 12, 1909.

Application filed May 16, 1908. Serial No. 433,174.

To all whom it may concern:

Be it known that I, WILLIAM F. DRAPER, a citizen of the United States, and resident of Hopedale, county of Worcester, State of Massachusetts, have invented certain new and useful Improvements in Loom-Shuttles, of which the following is a full, clear, and exact specification.

My invention relates to loom shuttles designed for the automatic insertion of a bobbin therein during the continuance in operation of the loom, and it has for its more particular object the production of improved means for engaging and holding in proper position the bobbin when inserted in the shuttle.

I effect the desired object by making separate jaws from resilient or spring plate metal, the shanks of the jaws being juxtaposed and securely held in the wood of the shuttle-body by appropriate means, and in order to lighten the jaws and at the same time improve their resiliency I make them of skeleton form. That is to say, each jaw has an elongated central opening extended from its free end toward its shank, the inner face of the jaw being provided with upright or transverse notches above and below the opening, to engage and hold the annular projections or rings on the bobbin-head. The jaws grasp the annular projections above and below a horizontal plane through the longitudinal axis of the bobbin, and thus hold it securely in position, the skeleton form of the jaws permitting them to yield more readily for the insertion and ejection of a bobbin.

Figure 1 is a top plan view of the bobbin-holding end of a loom shuttle provided with my improved holding means; Fig. 2 is a longitudinal section on the line 2—2, Fig. 1; Fig. 3 is a perspective view of one of the jaws; Fig. 4 is a similar view of the means for retaining the jaw shanks in place in the shuttle-body.

In Figs. 1 and 2 the numeral 1 is the shuttle-body, having an opening 2 for the reception of the bobbin, the head 3 whereof has annular projections or rings 4, Fig. 1, of common construction, and a narrow longitudinal recess 5 is made in the shuttle-body communicating with the bobbin-receiving opening 2, the recess being laterally undercut at 6, see dotted lines Fig. 1, the recess being open at its top.

The bobbin-holding jaws are made sepa-

rate and counterparts of each other, to be reversible, and they may be struck up or died out from resilient plate-metal. A jaw is shown separately in Fig. 3, it comprising an elongated portion or jaw proper 7, bent inward at its inner end at 8 and again bent to form a shank 9 which is substantially parallel to the jaw portion 7, but set in from the plane thereof, and apertured at 10. The jaw has an elongated central opening 11 extended longitudinally from its outer end to the bend 8, and herein I have shown such opening as continuing along the bend to the shank and gradually decreasing in width, as at 12. The inner face of the jaw is provided with upright or transverse notches or grooves 13, separated by the opening 11 into two series of alignment with each other and adjacent the upper and lower edges of the jaw, as very clearly illustrated in Figs. 2 and 3.

By making the jaw of skeleton form its weight is decreased while its spring or resiliency is increased and it will yield or flex more easily when a bobbin is being introduced to or ejected from the shuttle, requiring less power for the performance of such operations.

Inasmuch as the proper holding of the projections on the bobbin-head depends upon grasping the same above and below a horizontal plane extended through its longitudinal axis the opening 11 in no way interferes with the proper action, for the series of notches 13 above and below such opening can grasp and hold securely the projections 4 at the proper points.

By gradually reducing the width of the opening toward the shank 9 the parts of the jaw gradually increase in stiffness to the part where rigidity is desired, viz: the shank, as will be apparent.

The connection or bar 14 at the free end of each jaw unites the notched parts above and below the opening 11 and prevents accidental distortion or bending of such parts.

The jaw shanks 9 are placed face to face with the holes 10 registering, between the upturned sides 15 of a retaining member, made of plate metal and bent into the shape shown in Fig. 4, the bottom 16 being bent up at one end at 17 and then forward at 18, the top 18 being laterally widened to extend beyond the sides 15. The shanks 9 snugly fill the space between said sides, and between the bottom 16 and top 18, as shown in Fig. 2,

and holes 19 in the sides are made to register with the holes 10. At its front end the top 18 is narrowed and bent down at 20 to overlap a substantially crescent-shaped enlargement 21 of the bottom 16 of the retaining member, the bends 8 of the jaws resting upon the horns or tips of the enlargement, as shown in Fig. 1. The assembled parts are now placed in the shuttle, the sides 15 fitting snugly between the side walls of the recess 5 in the shuttle-body while the overhanging edges of the top 18 enter the undercut portions 6 of the recess; the bottom of the latter sustaining the bottom 16 of the retaining member. A transverse bolt 22 is then passed through a hole in the shuttle-body and through the holes 10 and 19, a nut 23, Fig. 1, securing the bolt in place, thereby holding the retaining member and the jaws firmly in place in the shuttle.

The jaws and the retaining member are easily and cheaply made and are readily assembled and inserted in the shuttle.

Having fully described my invention, what I claim as new and desire to secure by Letters Patent is:—

- 25 1. A loom shuttle provided with a bobbin-receiving opening and having holding-jaws mounted in one end thereof, the free ends of the jaws being open longitudinally between their upper and lower edges and provided on their inner faces with opposite upright notches to engage annular projections on the head of a bobbin.
- 30 2. A loom shuttle provided with a bobbin-receiving opening and having a recess in the shuttle-wood at one end thereof, separate holding-jaws having their shanks extended into the recess, and means to engage and hold the shanks rigidly therein, the free ends of the jaws being open along their central portions and having upright notches in their

inner faces above and below the open portions.

3. A loom shuttle provided with a bobbin-⁴⁵ receiving opening, longitudinally-extended and opposite skeleton jaws mounted on the shuttle body and having alined series of upright notches on their inner faces adjacent their upper and lower edges.

4. Bobbin-holding means for loom shuttles, comprising a pair of resilient, opposite jaws having their shanks set in from the planes of their free ends, each jaw having an elongated central opening extended longitudinally thereof from its outer end to the shank, and upright notches in the inner face of each jaw above and below the opening therein.

5. A loom shuttle provided with a bobbin-⁶⁰ receiving opening and having means at one end of the opening to grasp and hold the head of a bobbin, said means comprising separate skeleton spring-jaws having upright notches on their inner, opposite faces, ⁶⁵ and means to fixedly retain the jaws in place.

6. A loom shuttle provided with a bobbin-receiving opening and having holding-jaws mounted in one end thereof, the free ends of the jaws being open longitudinally between ⁷⁰ their upper and lower edges and provided on their inner faces with opposite upright notches to engage annular projections on the head of a bobbin, the longitudinal opening of each jaw gradually decreasing in width toward its ⁷⁵ shank.

In testimony whereof I have signed my name to this specification in the presence of two subscribing witnesses.

WILLIAM F. DRAPER.
